W. E. FRAWLEY, JR.

TWYER.

APPLICATION FILED JUNE 14, 1920.

Patented Sept. 13, 1921.

FIG. 2.

FIG. 4.

INVENTOR
W. E. FRAWLEY JR.

BY ATTORNEY

UNITED STATES PATENT OFFICE.

WILLIAM E. FRAWLEY, JR., OF BIRMINGHAM, ALABAMA.

TWYER.

1,390,694.

Specification of Letters Patent. Patented Sept. 13, 1921.

Application filed June 14, 1920. Serial No. 388,826.

To all whom it may concern:

Be it known that I, WILLIAM E. FRAWLEY, Jr., a citizen of the United States of America, residing at Birmingham, in the county 5 of Jefferson and State of Alabama, have invented certain new and useful Improvements in Twyers, of which the following is a specification.

My invention relates to twyers and more 10 particularly to twyers for Bessemer converters.

In the present state of the art the converter twyers, which are inserted upwardly through the converter bottom, are provided

15 with a bottom flange or lip at the base of their untapered round or rectangular bodies. These twyers pierce the bottom refractory lining and in service are subject to rapid deterioration and breakage. When a fracture 20 occurs a twyer is thereafter rendered useless, the released portion being blown out by the blast.

The object of my invention is to design a simple and effective means for materially increasing the life of such twyers and to this 25 end I provide them with a body tapering toward the twyer outlet and I incase this body in a jacket of any suitable tough or hard material capable under exposure to the 30 converter heat of withstanding greater strains than the refractory material forming the body of the twyer. This jacket is tapered to conform to the external taper of the twyer so as to hold the latter in operating 35 position even when a number of fractures have occurred in its refractory body, as the pieces cannot separate as they are held fixed by the taper jacket and thus cannot escape through the reduced end of the 40 jacket.

My invention also contemplates a simple and convenient manner of applying and interlocking the jacket with the twyer.

My invention also comprises the details 45 of construction and arrangements of parts, which in their preferred constructions only, are illustrated in the accompanying drawings which form a part of this specification, and in which:—

50 Figure 1 is a vertical cross-sectional view through a converter bottom.

Fig. 2 is a longitudinal sectional view enlarged of one of the twyers.

Fig. 3 is a bottom end view of Fig. 2.

Fig. 4 is a fragmental view of a modified 55 type of twyer.

Similar reference numerals refer to similar parts throughout the drawings.

In the embodiment of my invention illustrated, I show a typical bottom 1 of a Bessemer converter having a bottom plate 2 suitably connected to the wind box 3. The bottom plate is provided with the customary group of tapered twyer holes and through these holes the twyers are inserted upwardly 60 with their outlets 4 at the level of the refractory bottom that supports the metal bath.

The twyers are all of substantially the same construction and a description of one 70 will serve for all. The twyer is composed of a body of refractory material 5 having at its bottom end a flaring shoulder 6 and from this shoulder the body tapers gradually and slightly to its outlet 4. The shoulered end 6 of the refractory body is provided with a pair of opposing longitudinal slots 7 therein adapted to permit the passage therethrough of the retaining lips 8 which overhang from the flaring bottom end 9 of the twyer jacket 10. This jacket 10 may be made of any suitable metal or other material of tougher or greater tensile strength, or having higher heat resisting qualities than the refractory twyer body 5, 80 and it is shaped to fit snugly about the twyer body fram base to outlet end, and to interlock with the base of the twyer by having the lips, after passing through the twyer slots 7, moved out of register with the slots. 90 thus interlocking the jacket and twyer. The jacket terminates flush with the outlet end 4 of the twyer and may be provided with a reinforcing and retaining ring or flange 11 applied to or cast integral therewith and 95 adapted by engagement with the refractory converter bottom to better anchor the twyer in operating position.

In Fig. 4 I show a modified type of twyer having its outlet end reduced to form an 100 annular shoulder 12 which will fit against and interlock with an annular internal shoulder 13 provided at the inner end of the jacket 10.

In operation, having assembled the jacket 105 on the twyer, the twyer as a whole is inserted upwardly through the bottom plate 2 and secured in position in any customary

manner. When the blast is turned on and the converter is under operation, if a fracture occurs in the refractory body 5 of the twyer, its upwardly tapered structure will 5 prevent the loosened end being blown out as it will be held in the tapered jacket and the life of the twyer will thus be extended so long as the jacket itself will hold the twyer parts assembled. In ordinary service 10 the present type of expensive twyers have an average life of from thirty to thirty-five heats, whereas if the body could be held intact its life would be indefinitely extended.

Having thus described my invention, what 15 I claim as new and desire to secure by Letters Patent, is:—

1. A twyer formed by a refractory body tapered toward its outlet and having a close fitting tapering jacket inclosing and reinforcing the refractory body.

2. A twyer for converters comprising a refractory body tapering from its intake to

its outlet end, a refractory jacket tapered to fit snugly about the refractory body of the twyer, and means to connect the jacket and twyer body, substantially as described.

3. In a twyer for converters, a twyer proper of refractory material provided with a shoulder at its bottom and a body tapered slightly from said shoulder to outlet end, 30 there being longitudinal notches through said shoulder, a metallic jacket having a flaring base adapted to fit about the shoulder, and inturned lugs on the jacket base adapted to pass through the slots on the twyer shoulder and be moved out of register therewith to engage the bottom end about the body of the twyer thereon and being co-extensive therewith, substantially as described. 35

In testimony whereof I affix my signature.

WILLIAM E. FRAWLEY, Jr.
